UNITED STATES PATENT OFFICE.

ELEMIR J. NEY, OF DRACUT, ASSIGNOR TO JOHN H. PRAY, SONS & CO.,
OF BOSTON, MASSACHUSETTS.

DESIGN FOR CARPETING.

SPECIFICATION forming part of Design No. 11,607, dated January 13, 1880.

Application filed August 8, 1879. Term of patent 3½ years.

To all whom it may concern:

Be it known that I, ELEMIR J. NEY, of the town of Dracut, county of Middlesex, State of Massachusetts, have invented and produced 5 a new and original Design for Carpeting, of which the following is a specification.

The nature of my design is fully represented in the accompanying photographic illustration, to which reference is made.

I claim as my invention—
The design for carpeting, as shown in the accompanying photographic illustration.

ELEMIR J. NEY.
